CLAIM

The ornamental design for an integrated multi-sensored medical device, as shown and described.

DESCRIPTION

FIG. 1 is a top, front perspective view of an integrated multi-sensored medical device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plane view thereof; and,

FIG. 7 is a bottom plane view thereof.

The broken lines in the drawings depict parts of the integrated multi-sensored medical device that form no part of the claim.

1 Claim, 7 Drawing Sheets
